(76) Inventor: Scott Anton Chanlynn, Florence, WI (US)

* cited by examiner

() Term: 14 Years

Primary Examiner — Catheri Oliver-Garcia

(21) Appl. No.: 29/429,567

(57) CLAIM

The ornamental design for a plastic storage locker for golf equipment, as shown.

(22) Filed: Aug. 14, 2012

DESCRIPTION

(51) LOC (10) Cl. 03-01

FIG. 1 is a front view of the plastic storage locker for golf equipment;

(52) U.S. Cl.

FIG. 2 is a back view thereof;

USPC D3/255

FIG. 3 is a top view thereof;

(58) Field of Classification Search

FIG. 4 is a bottom view thereof;

USPC D3/255, 254, 259; 206/315.2-315.8

FIG. 5 is a left side view thereof;

See application file for complete search history.

FIG. 6 is a right side view thereof; and,

(56) References Cited

FIG. 7 is a perspective view thereof.
